DETACHABLE HEEL LIFT

John Kekoni, Anchorage, Alaska

Application September 4, 1935, Serial No. 39,129

5 Claims. (Cl. 36—42)

This invention relates to heel constructions for footwear in general and has more particular reference to a sectional heel construction for so-called high and low shoes, and the purpose of the invention is to provide a simple, economical and reliable construction wherein the detachable or separable lift is susceptible of expeditious application and removal.

Although the invention is not essentially destined to be used by any particular group or classification of people, it was conceived and perfected with the thought in mind of accommodating in particular persons in isolated areas where shoe repair facilities are not readily available. It is a matter of common knowledge, for example, that people in the far North or South, or in certain inland places have to do much of their own repair work and to obtain replacement and interchangeable parts by mail order service and otherwise.

It is evident, therefore, that all sorts of makeshift structures and appliances are employed in attempting to satisfy personal needs, and since shoe lifts are subject to ready wear and distortion from rugged use I have been influenced to develop and perfect a sectional heel construction which is aptly fitted for the purposes intended and calculated to overcome inconveniences and hardships now frequently experienced.

Although the invention is designed for general usage, it has to do with an arrangement which is especially feasible and practicable for employment along the lines above intimated. Therefore, in reducing the specific embodiment to practice I have evolved and produced an arrangement which is especially well suited for such purposes and which is, structurally and otherwise, distinctively different from sectional heel and replacement accessories with which I am now familiar.

Briefly, the preferred embodiment of the invention has to do with a relatively stationary or permanently attached heel section, a companion laminated lift construction and simple reliable coacting means for separably joining the two in operative relation and insuring effective jointing against accidental displacement through the instrumentality of controllable latch means.

Other features and advantages will become more readily apparent from the following description and drawings.

In the drawings:—

Figure 1 is a perspective showing of the detachable replacement lift.

Figure 2 is a perspective illustration of the embedded metal jointing plate.

Figure 3 is a view looking at the bottom of the relatively fixed section of the heel.

Figure 4 is a perspective drawing of the complementary anchoring plate associated with the fixed heel section.

Figures 5 and 6 are longitudinal sectional views taken approximately on the planes of the lines 5—5 and 6—6, respectively, of Figure 3, showing the lift attached or mounted in place.

Referring now to the drawings by distinguishing numerals it will be observed that the upper of the shoe is denoted by the numeral 1 whereas the attached sole is indicated at 8. This is provided in the heel attached area with a cut-out 9 which is in effect a clearance pocket or recess. Nailed or otherwise secured beneath this clearance groove 9 is the fixed section 10 of the heel structure. Interposed between these parts is the anchoring or adapter plate 11. This corresponds in shape with the part 10 and is provided with a series of substantially L-shaped flexible fastening and guide prongs or fingers 12. The central portion of the plate is slit to form a bendable tang 13 whose free end is bent laterally down as at 14 to serve as a keeper element. This depends into a keeper notch 15 cut in the frontal edge portion of the section 10.

The companion lift may be of one piece of material but is preferably composed of a ply of leather 16 having the rubber lift 17 fastened thereto. These parts 16 and 17 together with the intervening metal jointing plate 18 form the renewable or detachable lift 19. The heel-shaped jointing plate 18 is provided with a plurality of up-bent hanger lugs 20 apertured as at 21 to permit passage of the fingers 12 therethrough. Incidentally the fixed leather part 10 has rectangular sockets or openings 22 formed therein to accommodate the fingers 12 as well as the lugs 20 and to allow the parts to have the requisite relative sliding motion to facilitate coupling and uncoupling. The widths of the lugs 20 may correspond approximately to the widths of the socket 22 so as to guide the parts properly together. I next call attention to the numeral 23 in Figure 2 which designates an upstanding bendable or resilient latch which has its free end portion down-bent as indicated at 24 with the intervening features 25 and 26 properly shaped to provide a headed cam latch. This is cooperative with the aforementioned recess as shown in Figure 5 as well as the detent portion 14 of the liftable spring tang or keeper 13. Of course,

one might just as well refer to the parts 13 and 14 as a spring latch and the headed shank 23 as a keeper. It is evident, however, that however the parts are described by fitting the head 5 26 in the keeper notch 15, then matching the hanger lugs 20 with the sockets 22, the lift 19 is in readiness for proper placement in position. By lifting up the keeper 14, the part 19 can be shovved in a plane parallel to the part 10 feeding the fingers 12 through the openings 21 and thus 10 securely fastening the two parts 19 and 10 together in heel-forming relationship. The keeper 14 of its own accord drops down by spring tension to locking in position. When once it is 15 locked as shown in Figure 5 it can be lifted up by a suitable instrument inserted into the keeper notch 15. It may thus be said that the fixed part is provided with guiding and anchoring fingers 12 whereas the relatively movable part 19 is 20 provided with companion lugs. The lugs being insertable into the sockets 22 at right angles to the longitudinal dimension of the part 10 and then moved laterally in a horizontal plane to 25 separably join the parts together. The latching means is primarily to prevent retrograde movement of the part 19 and to avoid accidental displacement irrespective of rough usage and stubborn wear.

As is evident the invention is especially adaptable for the purposes intended, for it is sufficiently inclusive in its features and means to provide an adequate structure to supply the needs under ordinary ranking conditions. Beyond and more than this it provides a suitable arrangement widely useful to those located in sparsely populated areas where shoe repair-work cannot be conveniently attended to by specialized persons.

While the two metal plates are associated in 40 particular ways with the parts 10 and 19 it is obvious that they may be reversed and for this reason the plates will be referred to as the coacting jointing means between the heel sections. The parts are separately and collectively important 45 inasmuch as the heel may be built on to a shoe at the time of manufacture, or the parts separately obtained from proper sources and applied in an obvious home-made fashion. The succeeding claims should therefore be interpreted 50 accordingly.

It is thought that the description taken in connection with the drawings will enable a clear 55 understanding of the invention to be had. Therefore, a more lengthy description is thought unnecessary.

While the preferred embodiment of the invention has been shown and described, it is to be understood that minor changes coming within the field of invention claimed may be resorted to if desired.

What is claimed is:—

1. As a component part of a structural assem-

blage of the class described, a heel ply adapted for fixed connection with the sole of a shoe, an adapter plate mounted thereon, said adapter plate being provided with a plurality of guide and anchoring fingers, said ply being provided with enlarged openings surrounding said fingers to render them accessible, said ply being further provided at a predetermined point with a keeper notch, said plate having a flexible tang formed with a depending detent movably mounted in 10 said notch in the manner and for the purposes described.

2. As a new article of manufacture and a component part of a heel assemblage of the class described, an adapter plate of U-shaped configuration provided with a plurality of outwardly struck L-shaped resilient guiding and anchoring fingers, the intermediate portion of the plate being slit to provide a flexible tang and the free end thereof being extended and bent laterally in 15 relation to the body of the plate to function as a retention detent.

3. As a new article of manufacture and component part of a sectional heel construction of the class described, a hanger plate of heel-shaped 25 configuration provided with a plurality of upwardly struck laterally bent apertured hanger lugs, the frontal edge portion of said plate being further provided with an upstanding shank having a cam-shaped head formed on its upper end 30 to serve as a retaining latch or catch.

4. As a new article of manufacture, a detachable heel comprising a lift, a plate secured to the top of said lift, a complementary ply of leather secured to said lift, and substantially covering 35 said plate, said plate being provided with a plurality of upstanding apertured hanger lugs extending upwardly through and beyond said leather ply, and the frontal edge portion of said plate being further provided with an upstanding 40 shank having a cam-shaped head exposed through said leather ply.

5. In a structure of the class described, a relatively fixed heel ply, an adapter plate mounted thereon, said adapter plate being provided with a 45 plurality of guide and anchoring fingers, the associated heel ply being provided with enlarged openings surrounding said fingers to render them accessible, said ply being further provided with a keeper notch, said adapter plate having a flexible 50 tang formed with a depending detent movably mounted in said notch, a detachable heel lift disposed directly beneath and in separable contact with said heel ply, said lift including a permanently attached hanger plate having apertured 55 lugs releasably engageable with said fingers through the instrumentality of said enlarged openings, said hanger plate also including an upstanding shank having a cam-shaped head projecting into said notch and releasably connected with said detent.

JOHN KEKONI.
